UNITED STATES PATENT OFFICE.

ROBERT MORGENEIER, OF OAKLAND, CALIFORNIA, ASSIGNOR TO ROBERT FORD JACKSON, OF OAKLAND, CALIFORNIA.

BRIQUET-MACHINE.

No. 826,046.

Specification of Letters Patent.

Patented July 17, 1906.

Application filed September 7, 1905. Serial No. 277,430.

To all whom it may concern:

Be it known that I, ROBERT MORGENEIER, a citizen of the United States, residing at Oakland, in the county of Alameda and State of California, have invented certain new and useful Improvements in Briquet-Machines, of which the following is a specification.

My invention relates to the manufacture of compressed fuel, but more particularly to the machine for the compression or solidification into briquets of coal or other loose or specifically light materials singly or in combination with bituminous or other cementitious substances and the compression of particular materials requiring the presence of considerable heat both in the materials acted upon and in the compression-chambers and pistons of the press itself.

The object of my invention is to provide an automatic briquet-press of superior yet relatively simple construction, the operation of which shall enhance the quality of the product and reduce the cost of manufacture, and which machine or press shall also be self-cleaning, self-feeding, self-lubricating, and self-adjusting as relates to the pressure employed in forming the briquets.

With these objects in view my invention consists in the improved construction and novel arrangement of parts of a press, as will be hereinafter more fully described and afterward specifically pointed out in the appended claims.

Referring to the accompanying drawings, which illustrate the invention, Figure 1 is a broken top plan view of my improved briquet-press. Fig. 2 is a broken side elevation of the same with some parts in cross-section and others omitted or shown in part only. Fig. 3 is a similar view of the opposite side of the machine. Fig. 4 is a broken front end elevation on a smaller scale, partly in section and partly diagrammatic, of any pair of pistons when at the point of greatest separation. Fig. 5 is a broken elevation of any one pair of pistons when passing between the upper and lower compression-rolls to give the final pressure to the briquets. Fig. 6 is a plan view of the ejector-arms. Fig. 7 is a plan and sectional view, respectively, of the adjustable stud-bolts employed to draw down the spindles or pistons to the lower parts of an inclined track under a part of the press.

Like characters of reference indicate the same parts throughout the several figures. 55

I now proceed to describe the construction and operation of my said press, viz:

On a sole-plate 1 a flanged pedestal 2 is mounted, and centrally and vertically in the pedestal 2 a shaft 3 is rigidly secured. At 60 the upper end of the pedestal is formed a flange 4, Fig. 2, forming a broad horizontal bearing-surface. In the face of the flange and concentric with the shaft 3 is formed a channel 5, within which are placed cold- 65 chilled steel balls 6, thereby providing a proper bearing-surface for a disk 7, preferably of cast-iron. Within the disk 7 is formed a downwardly-projecting flanged sleeve 8, forming the hub of the disk, the flange being 70 faced and grooved for the reception of the balls 6, similar to the flange 4. The bore of the sleeve 8 is such that the vertical shaft 3 fits it, and when the disk is mounted as shown it may be revolved about such shaft after the 75 manner of a loose pulley, and its weight will be carried by the ball-bearing 6. As shown in the drawings, the disk 7 is shaped like an inverted circular pan, the sides of which are vertical and sufficiently thick to permit of 80 vertical cylindrical perforations 9 being formed therein. These perforations form receptacles or chambers and are preferably equidistant apart, smooth-bored, and each one provided with an external port 10 and an 85 internal port 11. Each port 10 is preferably provided with a gate 10', which is movably mounted in suitable guideways or channels formed in the wall at that point and extending along the sides of a recess above the port. 90 The disk 7 is further vertically perforated by bore-holes 12, arranged in pairs and set on the same circle as the perforations 9, the holes of each pair being upon opposite sides of and equidistant from the center of its perforation. 95 In the upper face of the disk 7 is formed a circular channel 13, with radiating branch channels 14 and 14' leading, respectively, to the perforations 9 and 12. Secured to or formed upon the peripheral circumference of 100 disk 7 is a material-supply trough 15, which communicates with the perforations or chambers 9 through the ports 10, said ports being preferably inclined forward, as shown by dotted lines in Fig. 1.

Rigidly secured to the peripheral circum-

ference of disk 7 is a beveled toothed rack or gear 16, the teeth of which mesh with a pinion 17, mounted on a shaft 18, and thereby rotate the disk at a prearranged rate of speed. Upon shaft 18 are also mounted a driving-pulley 19 and a loose pulley 20. The shaft 18 is held in a box 21, formed in a vertical frame-piece 22, which latter is rigidly bolted upon the sole-plate 1. The frame-piece 22 projects above and also overhangs the disk 7 and has formed upon its overhanging portion or horizontal flange 22' and above the center of the revoluble disk a bored boss 23, into which projects the upper end of the vertical shaft 3. A dowel-pin 24 firmly connects the frame-piece and the shaft, forming an arch under which any part of the disk 7 may be progressively rotated. Secured to the lower side of the flange 22' is a hanging bearing 25, Fig. 2, carrying a chilled-steel roller 26, the center of the axis of which is exactly over the center of each of the perforations 9 when such perforations are in position for the briquet to receive its final pressure. Rigidly mounted on the flange 22' at B', B², and B³ is a circular frame-piece 27, which overhangs the disk 7, excepting about one-fourth thereof commencing where the roller 26 is mounted. It is of the same diameter as the disk and is provided with downwardly-projecting walls in which are formed cam-tracks 28 and an overhanging guide-track 29.

Rigidly mounted on the sole-plate 1 is a cam or undulating circular track 30, which is of the same external diameter as the disk 7 and so set in relation to such disk that the vertical walls of each are flush one to the other.

Pivotedly mounted on a pin or stud 33 is a lever 32, in the head or inner end of which is seated a chilled-steel roller 31. The upper face of the head is preferably flattened, as at 32', which together with the roller 31 forms a part of the track 30, as shown more particularly in Fig. 5. The free end of the lever is provided with a shiftable weight 32'', by means of which the pressure to be applied to the briquets can be adjusted or regulated as desired or to suit the condition of the material being used. The axis of the rollers 31 is parallel with the axis of the roller 26 and vertically under it, so that when the perforations 9 pass between said rollers the axis of each of the perforations, if extended, would intersect the axes of the rollers substantially at their centers.

Rotatably and reciprocally mounted in the perforations 9 of the disk 7 are lower former-pistons 34, of steel, the upper ends of each piston being formed concave and preferably reinforced by a hardened tool-steel ring 34'. In the lower end of each of the pistons 34 is formed a chamber having therein a chilled concave steel plate 35, against which rest chilled-steel balls 36, forming a movable

crown-bearing for a larger chilled-steel ball 37. Above the smaller balls and steel plate is a lubricating-chamber for graphite and oil, and a channel 38 leads downward to such chamber. Around the lower end of the piston in the sleeve 34'' is formed a concaved groove 38'. Exactly above each one of the former-pistons 34 and rigidly secured to guide-pins 39, which slide in the bored ways 12, is a downwardly-extending working former-piston 40, the lower end of which is concaved, as shown, and the upper end fitted with ball-bearings the same as the lower ends of pistons 34, but housed in a rectangular head-block 41. Two of the opposite sides to 80 the blocks 41 are provided with lugs 42 and 42', preferably by curving the under surface of said sides, which are adapted to be engaged by the cam-tracks 28, and thereby lift the blocks and pistons 41 upward as the disk is rotated.

Vertically mounted in the cam frame-piece 28 are two horizontally-swinging briquet-ejector arms 43 43', which are curved and held by springs 43'' in such a manner that their radius intersects the centers of the perforations 9, as shown in Fig. 6. The arm 43' is intended to be supplementary to arm 43 and is preferably provided with a depending flange 43''', which will throw off any pieces of 95 material that may fall on top of the disk 7.

Rigidly mounted on the sole-plate 1 are posts 44, 44', and 44''. On the posts are head-pieces 45, 45', and 45'', in which is firmly held a circular bent rail 46. On the rail are mounted sliding clamp-blocks 47, 48, 49, 50, 51, and 52, each provided with a lug which overhangs the material-supply trough 15. Pendent from the lugs and standing vertically within the trough next to its interior outer side are adjustable stems 53, 54, 55, 56, and 57, to which are adjustably attached stationary plows 58, 59, 60, 61, and 62, respectively.

Extending from C to D around the side of the disk 7 is a stationary iron deckel or shield 63, suspended from the framework above the disk and closely fitting against the side thereof. It is preferably provided with a rib or flange 63' to give it the required stiffness or 115 rigidity. At the head of the shield 63 near C is a pivoted and laterally-adjustable gate or wing-dam 64, which is of a less height than the top of the trough 15 and is supported by the clamp-block 52.

Within the disk 7 and directly under the same, but unconnected therewith, is mounted a steam-coil 65, Fig. 3, fitted with a supply-valve 66 and a drip or exhaust valve 67. There is also set up under and within the disk and unconnected therewith a steam-pipe 68, fitted with a nozzle 69 and shut-off valve 70.

On the downgrade of the lower cam-track 30 are formed flanges 71 and 71', in which are fitted stud-bolts 71'', which are adapted to 130

engage with the grooves 38" and withdraw the pistons to their lowest points as the disk is rotated. The bolts are adjustable, and those from the outside are adapted to hold 5 the lower end of each piston toward the center of the press, and thereby avoid undue friction at the point where the piston enters the lower face of the disk. The bolts are held in their adjustable position by ordinary jam-nuts. An additional device for the prevention 10 of this friction of the piston with the disk both in the descent and rise thereof is the inclined upper surface of the track 30, plainly shown at 30' in the cross-section of Fig. 7. 15 This incline is greatest at the lowest point of track and from thence gradually resolves itself into a level at the highest point where the pistons only project slightly from the lower disk-surface. The percentage of gradual incline is so calculated that all "drag" and 20 "chatter" of the pistons when in operation is avoided.

From the above description it is evident 25 that when the disk 7 is rotated the former-pistons that are revolved or carried around with it will ride respectively on and under the stationary tracks or cams, and during the progress of such revolution will be lifted upward or forced downward agreeable to the rise or 30 fall of these surfaces. Thus when pistons 34 reach the extreme front of the machine, as shown in Fig. 3, they are at the lowest point of the plane. When opposite the beveled pinion 17, Fig. 2, they are at the point where 35 the press exercises its greatest pressure—viz., the upper and lower pressure-rolls are closer together than at any other two points of the lower track 30 and upper track 29, and the piston is directly therebetween, as shown in 40 Fig. 5. Further, when the pistons approach the upper cam-track 28, Fig. 3, they are on the highest altitude of the lower track, and it is here that the finished briquets approach the ejector-arms hereinbefore described.

45 When the former-pistons are at the lowest point of the track 30, their concaved upper end is somewhat lower than the bottom line of the charging-ports 10, Fig. 3, while at the highest altitude such end projects above the 50 upper surface of the disk 7. At this highest point, commencing with a level plain and then descending gradually to the lowest point, the track 30 carries the two side lugs 71, (shown in Figs. 3 and 7,) which lugs are fitted 55 with adjustable bolts closely set together. When the former-pistons traverse the level plain of the track 30, the rounded ends of said stud-bolts engage the concaves 38" and so continue in contact during the descent of the 60 pistons, thereby absolutely insuring the lowering of the pistons by fixed means and not by gravity alone, and also avoiding undue friction and chattering.

The upper former-pistons 40 have a more 65 limited vertical motion than the piston 34,

which is controlled by four factors, as follows: First, they are pressed downward when rotating under the cam-track 27; second, they are forced downward when passing under the compression-roller 26; third, they are raised 70 by the upward motion of the former-piston 34 after a briquet has been formed and is still held between the two pistons, and, finally, they are again raised by means of their convex lugs and the cam-track 28, all of which motions are repeated with every rotation of the disk 7.

As heretofore stated, the material-supply trough 15 rotates with the disk, and within it stand the fixed plows 58, 59, 60, and 62, all 80 pointed toward the rotary moving force of the disk and trough with the moldboards curved toward the outer circle of the disk, all to the end that when the trough is steadily supplied with material for briquets this material in rotation will be constantly plowed turned over, and thrown against the disk, and forced into the piston-chambers by way of the ports 10. The exterior of the trough is preferably covered with asbestos, so that 90 no heat contained in the briquet materials may be lost by radiation. After passing the plows the material is engaged by the wing-dam 64, which is pointed at a slight angle into the current of rotating material, and thereby 95 diverts as much of the same into the ports as may be needed to completely fill the cylinder-chambers before the shield closes the ports. Any surplus material will overflow the wing-dam, the top of which is lower than the sides 100 of the trough, and the material within the ports is prevented from escaping by the shield.

When coal and bituminous cementitious materials are employed in the manufacture 105 of briquets, the proper temperature of such material and of the forming-chambers and piston is of the utmost importance, and I propose to control such temperature by means of the steam devices shown. The piston and chambers must be kept hot and clean, and this I effect by the use of steam from the pipe 68, entering through the ports 11, the port being cored out upon its interior, so that 110 the pistons are exposed to the heat all around. 115

After the briquets have been formed and successively presented on the top of former-pistons 34 to the ejector-arms, the upper pistons 41 having been previously raised entirely clear of such briquets, they will be ejected 120 outward by the arms, the second arm being supplementary to the first.

The ball-bearing for supporting the disk and the compound ball-bearing in the heads of the former-pistons 34 and 41 are provided 125 in order to reduce the friction to a minimum and to provide universal motion at the said piston ends and at the same time assure perfect contact of all working parts when the pistons with briquet material between their 130

ends are passing under the compression-rollers 26 and 31.

- By providing the lever with a shifting adjustable weight it is possible to secure the exact pressure needed to form perfect briquets from any certain material or combination of materials. By this arrangement of the lever a perfectly-solidified briquet may be produced even if the supply of briquet material entering the various pockets should differ somewhat in quantity at times, as the lever will adjust and still maintain the pressure required. The force exerted will be both upward and downward and simultaneous, and, further, such two forces will be deflected toward the center of the briquet being formed, such deflection being general over the said surfaces. The resulting briquet will be hard and glossy on its entire surface.
- 20 The briquets are ejected as fast as made, and the press, as shown, and revolved at the rate of fifteen revolutions per minute, will produce seven tons of briquets per hour without undue wear upon the parts of the machine.

Although I have shown and described what I consider the best means for constructing a machine embodying my invention, it is evident that changes or alterations can be made therein, and I reserve the right to make all such modifications as will come within the scope of my invention. For instance, by providing the channel 13 in the top of the disk with a suitable material the briquets 35 may be provided or coated with a glaze, and by feeding the material to the upper end of the perforations after the lower plungers have commenced their descent, as shown by dotted lines in Fig. 3, the capacity of the press 40 may be increased, owing to the less amount of material that must enter through the ports 10 and the corresponding increase of speed at which the disk may therefore be driven.

Having now fully described my invention, 45 what I claim as new, and desire to secure by Letters Patent, is—

1. In a briquet-press, the combination, with a revoluble disk provided with a vertical, circular chamber therein and an external 50 side port opening into the chamber and a lower internal port opening into the interior of said disk, from the said chamber.
2. In a briquet-press, the combination, with a revoluble disk provided with a series 55 of vertical, circular chambers formed therein and in a circle concentric with the periphery of said disk and provided with ports opening to the exterior and interior of the disk.
3. In a briquet-press, the combination, 60 with a revoluble disk provided with a plurality of internal and external ported chambers, and means for charging said chambers by way of the external ports.
4. In a briquet-press, the combination, 65 with a revoluble disk provided with a plural-

ity of external and internal ported chambers, and means for cleaning and heating said chambers by way of the internal ports.

5. In a briquet-press, the combination, with a revoluble chambered, ported and troughed disk, of stationary plows for throwing material into the chambers, a stationary shield, and an adjustable head-gate for diverting and packing material into the chambers and closing the ports thereof every time 75 the chambers have been so filled.

6. In a briquet-press, the combination, with a revoluble, chambered, internally-ported disk, of means for heating and cleaning such chamber by way of said internal ports. 80

7. In a briquet-press, the combination, with a revoluble disk, chambered and provided with internal ports opening up into each chamber, and a steam-pipe with nozzle directed toward said ports, so that when the 85 disk is rotated a jet of steam may be caused to enter the said internal ports and chambers.

8. In a briquet-press, the combination, with a revoluble disk provided with vertical chambers formed in the body thereof near its 90 periphery, and a steam-heating coil placed within and under the disk to heat the same.

9. In a briquet-press, the combination, with a revoluble disk provided with vertical cylinder perforations and vertical guide-pin 95 holes, and a circular oil-channel and radiating channels therefrom connecting with all of the perforations and holes.

10. In a briquet-press, the combination, with a top former-piston, one end of which is 100 concaved, the other terminating in a ball-bearing, a head-block for said bearing, said block having formed on its bottom and two opposite sides, convex lugs and guide-pins projecting from said block. 105

11. In a briquet-press, the combination, with a revoluble chambered disk, with guide-holes bored in the top thereof, top and bottom former-pistons in said chambers, guide-pins connected with the top pistons and sliding vertically in the holes, and means for imparting vertical motions to the former-pistons and guide-pins when the disk is rotated. 110

12. In a briquet-press, the combination, with a rotary member of a vertically-movable rotary former-piston mounted therein, the lower end of which is provided with a ball-bearing, a cam or undulated stationary track under the center of said piston, the upper track-surface of which is curved or inclined 115 inward at some of its length and level at others, whereby when said piston is carried around in a circle by the disk and its ball-bearing contacts with the said track-surface it will move upward and downward agreeable 120 to the elevation and depression of such track, and its lower end will be held toward the center of rotation when it is moving on the inwardly-inclined part of the track.

13. In a briquet-press, the combination, 125

with a rotary member, of a series of vertically-movable, rotary lower former-pistons mounted therein, a cam or undulated stationary track under the centers of said pistons and having undulations and inclined surfaces, a pivoted fulcrum - head, a steel roller mounted therein and crosswise of the track, said fulcrum and roller being pivotally movable, but otherwise forming an integral part of such track.

14. In a briquet-press, the combination, with a series of peripherally-depressed rotary former-pistons, of an undulatory inclined track, flanges formed on the sides of a part of such track, adjustable bolts in said flanges which engage in said depressions of the pistons at their extreme lower ends.

15. In a briquet-press, the combination, with a rotary pin-guided upper former-piston provided with a head-block, a ball-bearing in said block, an overhanging depresser-track formed over a section of the circle of rotation of such piston and contacting by its lower surface with the ball-bearing in the head-block of the piston.

16. In a briquet-press, the combination, with a rotating upper former-piston, of convex raising-lugs formed at the head of the piston, and a circular jaw-cam overhanging the circle of rotation of the piston and engaging the convex lugs thereof, whereby said piston is raised from any briquet formed by it, and a lower former-piston.

17. In a briquet-press, the combination, with a series of rotating upper former-pistons, each provided with a ball-bearing, of depression and elevating tracks and lugs, and a compression - roller set transversely to the circle of rotation of said pistons and above the same, whereby when the ball-bearing in the head-block of each piston, in passing under the roller, will encounter the same and be rotated and the piston will be depressed.

18. In a briquet-press, the combination,

with a plurality of vertically-arranged chambers, of means for feeding material laterally thereto, and means for compressing said material within the chambers.

19. In a briquet-press, the combination, with a rotary member provided with a plurality of vertical chambers, each provided with a forwardly-inclined port, of means for feeding material laterally thereto, and plungers for compressing said material within the chambers.

20. In a briquet-press, the combination, with a flanged disk provided with a plurality of vertical chambers, each open at both ends and provided with a port intermediate its length, of means for feeding material thereto, reciprocatory plungers in each of said chambers, means for simultaneously moving said plungers in opposite directions to compress the material and means for discharging the complete briquets.

21. In a briquet-press, the combination, with a vertically-perforated rotary member, of means for feeding material thereto, two members in each perforation, the outer ends of which are each provided with a ball-bearing, inclined tracks for reciprocating the plungers, a lever, the head of which is flat and recessed, a roller in said recess, said flat portion and roller forming a part of one of the tracks, a weight adjustably mounted on the outer end of said lever, and a roller in the other track, said rollers being so located as to be simultaneously engaged by said plungers to give the final compression to the briquets.

In testimony whereof I affix my signature, in presence of two witnesses, this 31st day of August, 1905.

ROBERT MORGENEIER.
